(57) **CLAIM**

The ornamental design for a terminal connector, as shown and described.

DESCRIPTION

FIG. 1 is a front-right side perspective view of the terminal connector;

FIG. 2 is a front-left side perspective view of the terminal connector illustrated in FIG. 1;

FIG. 3 is a rear-right side perspective view of the terminal connector illustrated in FIG. 1;

FIG. 4 is a rear-left side perspective view of the terminal connector illustrated in FIG. 1;

FIG. 5 is a front end view of the terminal connector illustrated in FIG. 1;

FIG. 6 is a rear end view of the terminal connector illustrated in FIG. 1;

FIG. 7 is a right side view of the terminal connector illustrated in FIG. 1, the left side view being a mirror image thereof; and, FIG. 8 is a top view of the terminal connector illustrated in FIG. 1, the bottom view being a mirror image thereof.

The portions of the device depicted in broken lines are for illustrative purposes only and form no part of the claimed design.
